UNITED STATES PATENT OFFICE.

RAYMOND PERCIVAL PAYNE, OF LEEDS, ENGLAND.

ROTARY PRINTING-MACHINE.

1,194,416.

Specification of Letters Patent. Patented Aug. 15, 1916.

Application filed January 16, 1914. Serial No. 812,438.

To all whom it may concern:

Be it known that I, RAYMOND PERCIVAL PAYNE, a subject of the King of Great Britain, residing at Leeds, in the county of 5 Yorkshire, England, have invented certain new and useful Improvements in Rotary Printing-Machines, of which the following is a full, clear, and exact description.

This invention relates to rotary printing 10 machines and has special application to machines in which more than one design is printed for each cycle of the machine. A machine of this character generally utilizes a plurality of rotary cylinders each of which 15 is adapted to carry either a single or a plurality of design surfaces which come into printing contact with the printing surfaces on an associated cylinder. It has heretofore been proposed to construct a machine of this 20 character so that the design cylinders can have a rotary adjustment imparted to them during their rotation for the purpose of altering the register of the design surfaces with the surfaces with which they come into 25 printing contact.

The object of my invention is to improve generally upon the devices which have been produced for this purpose and to provide a construction wherein the adjustment may 30 be accomplished in a simple and expeditious manner.

With these and other objects in view, my invention consists of a form of driving gear for rotating the cylinder, which gearing 35 comprises means including a member movable longitudinally with respect to the axis of one of the cylinders for effecting the rotary adjustment, without disconnecting the driving gear.

In the accompanying drawings, Figure 1 40 is a plan partially in section of the end portions of a design cylinder and an associated cylinder, together with a driving gear therefor, embodying the features of my invention; Fig. 2 is a detail view showing in elevation the main essentials of the driving gear shown in Fig. 1; Fig. 3 is a plan similar to Fig. 1 showing another modification of the driving gear; and Fig. 4 is a detail 45 view in elevation of a portion of the driving gear shown in Fig. 3.

Referring generally to the construction shown in Figs. 1 and 3, 1 designates a cylinder adapted to carry either a single or a plurality of design surfaces, and 2 designates

the cylinder associated therewith which is adapted to carry surfaces in printing contact with the design surfaces. The associated cylinder 2 may consist of an impression cylinder which is adapted to carry the sheets 60 upon which the design is to be printed, or if the invention is to be utilized in connection with an offset printing machine the cylinder 2 would constitute the transfer cylinder which would have on its surface the 65 blankets of rubber or the like adapted to receive the imprint of the designs, the invention being capable of utilization with any type of printing machine having two associated cylinders whose surfaces are in 70 printing contact. It may be here stated that while I have shown, for the sake of clearness, a single design cylinder, yet in the machine where the invention is particularly adaptable, there would be a plurality of 75 such cylinders, arranged in printing contact with the associated cylinder.

Referring now to Fig. 1, wherein one form of the improved driving gear for the cylinders 1 and 2 is shown, which is adapted 80 to simultaneously rotate the cylinders continuously and to impart thereto an additional rotary adjustment during their rotation. The cylinders 1 and 2 are mounted upon shafts 3 and 4, respectively, only a portion of which are shown. A gear wheel 5 is mounted upon the shaft 4 and is rigidly secured to the cylinder 2 by means of bolts 6. The gear wheel and connections for the design cylinder 1 comprise a hub 7 which is 85 mounted upon the shaft 3 to slide longitudinally thereon, and is prevented from independent rotation of this shaft by a key 8. Surrounding the hub 7 is an annular gear wheel 9 whose outer peripheral surface is 90 provided with teeth adapted to mesh with the gear wheel 5 carried by the cylinder 2. This annular ring or gear wheel is connected or secured to the cylinder 1 by means of bolts 10 passing through elongated segmental-shaped slots 10' in the same, which connection permits relative angular movement 95 between the gear wheel and cylinder, while preventing displacement of the gear wheel longitudinally of the axis of the cylinder. 100

If desired the gear wheel 5 carried by the cylinder 2 may be provided with an annular flange 11 and a portion of the outer peripheral surface of the annular ring or gear wheel 9 cut away to provide a recess form- 110

ing a shoulder 12 against which this flange bears, and therefore prevents any longitudinal movement of the annular gear wheel. The annular gear wheel 9 is connected to the hub 7 by a single key or a plurality of keys 13 sunk into the inner peripheral surface of the ring to hold them in place, which keys are adapted to fit into slots or keyways in the outer peripheral surface of the hub. These keys and keyways are arranged obliquely or at an angle to the axial planes of the cylinder so that upon movement of the hub longitudinally along its shaft the angular position of the gear wheel relative to the cylinder 1 will be changed, and therefore the design cylinder may be adjusted rotarily to provide the desired alignment between the printing surfaces of both cylinders. It is apparent that the key 8 might be set at an angle to the axial planes instead of keys 13, which construction would give the same result.

An annular groove or hub slot 14 is provided in an extension of the hub 7 into which is fitted a sliding collar 15. This collar is connected to a yoke lever 16 pivoted as at 17 to a stationary part of the machine. The other end of the lever 16 carries a thumb adjusting screw 18 which is mounted in trunnion bearings and has its end threaded into a stationary part 19 carried by the frame of the machine, not shown. To adjust the hub 7 longitudinally of the shaft 3, therefore, it is only necessary to turn the thumb screw 18 until the lever 16 has been moved the desired amount to obtain the adjustment, in which position the hub 7 will be held until it is again displaced by a further manual adjustment of the parts, the adjusted position being that in which the cylinders are in the desired register.

In Fig. 3, there is shown another modification for effecting the rotary adjustment which consists in loosely mounting a gear wheel 23 on the shaft of the cylinder 1 and connecting this gear wheel to the cylinder by means of slide-ways or guides 24 projecting from the end face of the cylinder, which slide-ways have their bearing surfaces inclined to the axial planes of the cylinder, passing through the same. The ends of these slide ways project through segmental shaped openings in the web of the gear wheel 23 and on the rib formed between the openings, a block 25 is pivotally mounted which block has its side faces cut at an angle to ride in the slide-ways 24.

While one such connection is shown, it is evident that if desired, a plurality of such blocks and slide-ways may be utilized in order to provide a more secure connection between the gear wheel and the cylinder. When the gear wheel is moved longitudinally on its shaft, the angular position of

the gear wheel with respect to the design cylinder will be changed and will thereby effect the rotary adjustment of the cylinders as has been described.

It will be apparent from the modifications herein set forth that the necessary rotary adjustment may be obtained in various ways without disconnecting the driving gear and it is not my intention to limit myself to any particular form, but only by the scope of the claims appended hereto.

I claim:

1. In a rotary printing machine, two cylinders operatively associated with each other, and adapted to carry printing surfaces, gearing connecting said cylinders, comprising a gear wheel mounted for rotation with one of said cylinders and a gear wheel and connections from said last named gear wheel to the other of said cylinders, said last named gear wheel and connections having a part mounted for rotation with said last named cylinder and a part capable of independent rotation thereto, one of said parts being movable longitudinally of the axis of said cylinder and means for causing an angular displacement of said independently rotatable part with respect to said cylinder upon the relative movement of said parts longitudinally of the axis of said cylinder.

2. In a rotary printing machine, two cylinders operatively associated with each other, and adapted to carry printing surfaces, gear wheels one for each cylinder in mesh with each other, one of said gear wheels being capable of independent rotary movement relative to its corresponding cylinder, means for connecting said gear wheel to its corresponding cylinder comprising a part mounted for rotation with said cylinder and a sliding connection between said part and said gear wheel capable of changing the angular position of said gear wheel with respect to its cylinder upon relative movement longitudinally of the axis of said cylinder.

3. In a rotary printing machine, two cylinders operatively associated and adapted to carry surfaces in printing contact, gear wheels connecting said cylinders, one of said gear wheels being loosely mounted on its shaft, means for connecting said gear wheel to said cylinder, and for effecting a change in the angular position of said gear wheel with respect to its cylinder upon longitudinal movement of said gear wheel on its supporting shaft.

4. In a rotary printing machine, two cylinders operatively associated and adapted to carry surfaces in printing contact with each other, gearing connecting said cylinders including a gear wheel loosely mounted on the shaft of one of said cylinders, slide-ways projecting from one of the end

faces of said cylinders which slide-ways have their surfaces inclined to the axial planes of the cylinders passing therethrough, and a pivoted block on said gear 5 wheel adapted to slide in the said slide-ways and means for moving said gear wheel longitudinally on its shaft.

In witness whereof, I subscribe my signature, in the presence of two witnesses.

RAYMOND PERCIVAL PAYNE.
